UNITED STATES PATENT OFFICE.

RAYMOND H. GARMAN, OF CHICAGO, ILLINOIS.

DESIGN FOR A BOOK OR BOOKLET COVER.

No. 38,643.

Specification for Design.

Patented June 25, 1907.

Application filed May 24, 1907. Serial No. 375,554. Term of patent 3½ years.

To all whom it may concern:

Be it known that I, RAYMOND H. GARMAN, a citizen of the United States, residing at Chicago, county of Cook, and State of Illinois, have invented a new, original, and ornamental Design for Book or Booklet Covers, of which the following is a specification, reference being had to the accompanying drawings, forming a part thereof.

The drawing shows in elevation the design of the book or booklet cover.

I claim,

The ornamental design for a book or booklet cover, as shown.

RAYMOND H. GARMAN.
